UNITED STATES PATENT OFFICE.

MIKE BINDAS, OF EAST HAMMOND, INDIANA, ASSIGNOR OF ONE-FOURTH TO DANKO KORNOFYL, OF EAST HAMMOND, INDIANA.

SAW-GUMMING DEVICE.

Application filed July 28, 1921. Serial No. 488,129.

To all whom it may concern:

Be it known that I, MIKE BINDAS, a citizen of the United States of America, residing at East Hammond, in the county of 5 Lake and State of Indiana, have invented certain new and useful Improvements in Saw-Gumming Devices, of which the following is a specification.

This invention relates to certain new and 10 useful improvements in saw gumming devices of that type involving a vertically slideable gumming die carrying plunger having a manually operable actuating lever.

The primary object of the invention is to 15 generally simplify and improve devices of the above kind whereby saws may be readily gummed in an expeditious manner.

Another object of the invention is to provide a saw gumming device wherein the 20 male die is provided with a simple and durable form of actuating mechanism, the members of which are separably connected so that any desired ones of the same may be renewed when broken or worn.

Other objects will appear as the nature of the invention is better understood and the same consists in the novel form combination and arrangement of parts herinafter 25 more fully described and shown in the accompanying drawing, in which like designating characters refer to corresponding parts throughout the several views.

In the drawing;

Figure 1 is a side elevational view of a 30 saw gumming device constructed in accordance with the present invention;

Figure 2 is a top plan view thereof;

Figure 3 is a view partly in front elevation and partly in vertical section along line 40 III—III of Figure 1, and

Figure 4 is a horizontal sectional view taken on line IV—IV of Figure 3 and partly broken away with a portion of a saw shown operatively disposed upon the bed plate of the device.

Referring more in detail to the several views, the invention embodies a one-piece casting including a base plate 5 adapted to be secured upon a suitable support such as 45 a bench top, a bed plate 6 above the base plate 5 and connected to the latter by an integral intermediate portion 7, and a guide post 8 extending upwardly from the bed plate 6 and having a cut out at its lower

end as at 9 so as to overhang the bed plate 55 6 as clearly shown in Figure 1. The plates 5 and 6 are preferably at right angles and the latter plate is provided with a central transverse groove 10 of dove-tail form for removable reception for a similar form of female 60 gumming die 11 which may be secured in place by means of a suitable set or stud screw 12 with its opening alined with a male die 13 which may be suitably removably attached to the lower end of a plunger 14 which is vertically 65 slideable in the central bore of the guide post 8. The rod 14 is sufficiently long to project upwardly beyond the upper end of the post 8 and this projecting portion of the rod 14 extends freely between the legs 70 15 of the bifurcated end of a suitable hand lever 16, which legs 15 have their free ends pivoted by means of a bolt 17 or the like to an ear 18 provided on the forward upper corner of the post 8. Each leg 15 is provided with a slot 19 in which the upper end of a link 20 is pivoted upon a screw 21 which extends through said leg, and the two screws 21 are provided with screw driver kerfs which are engaged by the flat- 80 tened ends of a U-shaped clip 22 which spans the bifurcated end of the lever 16 and is adapted to prevent unscrewing of said screws 21 accidentally. The U-shaped clip 22 may, however, be readily removed 85 for permitting intentional removal of the screws 21. The guide post 8 is provided with a pair of alined vertically elongated slots 23 intermediate its ends and communicating with the bore of said guide post, 90 and the lower ends of the links 20 are pivoted upon a bolt 24 which extends through the rod 14 and the slots 23, suitable spacing sleeves 25 being placed upon the bolt 24 95 between the links 20 and the rod 14 so as to maintain the links 20 parallel and prevent wobbling of the same. The rod 14 is provided with a longitudinal series of openings 26 for selective reception of the bolt 24 so that the throw of the lever 16 100 and rod 14 may be adjustably varied to suit the requirements for different saws to be operated on, and as the screws 21 and bolts 24 are readily removable, it will be seen that the links 20, rod 14 and lever 16 105 may be renewed from time to time as found necessary.

A depth gage 27 in the form of a flat plate

with a straight edge 28 is secured flatly upon the upper surface of the bed plate 6 by means of screws or bolts 29 which extend through elongated slots 30 in rearwardly extending tongues 31 carried by said gage 27 and which also extend through suitable openings in the bed plate 6. In this manner, the straight edge 28 is arranged longitudinally of the bed plate 6 and the gage 27 is fastened to the bed plate so as to be adjustable transversely of the latter, thereby adjustably gaging the depth of the cut made by the male die 13 when the teeth of the saw A are engaged with said straight edge 28 as shown in Figure 4. The depth gage 27 is preferably disposed at one side of the guide post, and a saw adjusting guide and indicator 32 is preferably secured to the base plate 6 at the other side of the post 8, said 15 guide and indicator 32 comprising a plate flatly secured against the upper surface of the bed plate 6 and having a forwardly projecting tooth 33 arranged to project into the space between adjacent teeth of the saw A 20 when the latter is properly disposed to be gummmed. The guide and indicator 32 is preferably adjustably attached to the bed plate 6 for movement longitudinally of said bed plate by means of a bolt 34 or the like 25 30 which extends through a suitable opening in the plate portion of said guide and indicator and also through a longitudinally elongated slot 35 provided in the bed plate 6. By varying the distance between the male die 13 and the tooth 33, the device may be made to accommodate saws wherein the teeth spacing varies and by engaging the tooth 33 between successive teeth of the saw, said saw may be expeditiously gummmed without 35 40 liability of missing any particular notch of said saw and with the assurance that the saw teeth will be in proper relation with the male die 13 when the latter is operated.

When using the device, the depth gage 28 and the adjustment gage and indicator 32 are properly set and the saw plate to be gummmed is placed flatly on the bed plate 6 as shown in Figure 4 with the points of the saw plate teeth bearing against the straight edge 28 and with the tooth 33 engaged between adjacent teeth of the saw plate. The male die 13 is then depressed through the medium of the hand lever 16 and in conjunction with the female die 13, it will shear or cleanly cut 50 55 the saw plate and thereby deepen and enlarge the space between adjacent teeth. This operation is repeated with reference to each of the spaces of the saw plate, said plate being of course properly adjusted subsequent to each gummging operation.

From the foregoing description, it is believed that the construction and operation as well as the advantages of the present invention will be readily understood and appreciated by those skilled in the art.

Minor changes may be made without departing from the spirit and scope of the invention as claimed.

What is claimed as new is:

1. A saw gumming device including a base 70 plate adapted to be secured upon a suitable support and integrally with a bed plate disposed thereabove, a guide post having a central bore and integrally connected with the bed and base plates, said guide post being 75 cut out at its lower end portion so as to overhang said bed plate, a female gumming die 80 removably secured to the bed plate, a vertically reciprocable rod mounted in the bore of said guide post and having a male die 85 upon its lower end arranged to cooperate with said female die as well as projecting upwardly beyond the upper end of said guide post, said guide post being provided with aligned vertically elongated 90 slots in the sides thereof communicating with the bore of the same, a lever having a bifurcated end portion between the legs of which the upper end of said rod freely extends, the free ends of said legs being pivoted to the upper end of said guide post, a pair of links, each having its upper end pivoted to one leg of the bifurcated portion of said hand lever and depending at one side of said guide post, a bolt projecting 95 through said rod and the vertically elongated slots of the guide post and having the lower ends of said links pivoted thereon and means to permit adjustment of said bolt at various points between the ends of said rod 100 whereby the throw of said lever is varied.

2. A saw gumming device including a base plate adapted to be secured upon a suitable support and integrally with a bed plate disposed thereabove, a guide post having a central bore and integrally connected with the bed and base plates, said guide post being cut out at its lower end portion so as to overhang said bed plate, a female gumming die 110 removably secured to the bed plate, a vertically reciprocable rod mounted in the bore of said guide post and having a male die upon its lower end arranged to cooperate with said female die as well as projecting upwardly beyond the upper end of said guide 115 post, said guide post being provided with aligned vertically elongated slots in the sides thereof communicating with the bore of the same, a lever having a bifurcated end portion between the legs of which the upper 120 end of said rod freely extends, the free ends of said legs being pivoted to the upper end of said guide post, a pair of links, each having its upper end pivoted to one leg of the bifurcated portion of said hand lever and depending at one side of said guide post, a bolt projecting through said rod and the vertically elongated slots of the guide post 125 and having the lower ends of said links pivoted thereon, means to permit adjustment of 130

said bolt at various points between the ends of said rod whereby the throw of said lever is varied, the legs of the bifurcated portion of the lever being provided with slots in which the upper ends of said links are pivoted, and spacing sleeves arranged upon said bolt between the lower ends of said links and said rod.

3. A saw gumming device including a base plate adapted to be secured upon a suitable support and integrally with a bed plate disposed thereabove, a guide post having a central bore and integrally connected with the bed and base plates, said guide post being cut out at its lower end portion so as to overhang said bed plate, a female gumming die removably secured to the bed plate, a vertically reciprocable rod mounted in the bore of said guide post and having a male die upon its lower end arranged to cooperate with said female die as well as projecting upwardly beyond the upper end of said guide post, said guide post being provided with aligned vertically elongated slots in the sides thereof communicating with the bore of the same, a lever having a bifurcated end portion between the legs of which the upper end of said rod freely extends, the free ends of said legs being pivoted to the upper end of said guide post, a pair of links each having its upper end pivoted to one leg of the bifurcated portion of said hand lever and depending at one side of said guide post, a bolt projecting through said rod and the vertically elongated slots of the guide post and having the lower ends of said links pivoted

thereon and means to permit adjustment of said bolt at various points between the ends of said rod whereby the throw of said lever is varied, the means for pivotally connecting the upper ends of the links to the lever comprising removable screws having notched heads, and a U-shaped clip having flattened ends engaging in the notches of said screws to prevent accidental unscrewing of said screws.

4. In a saw gumming device, a bed plate provided with a female die, an upright guide post having a vertically reciprocable rod slidable therethrough and said rod having a male die upon the lower end thereof arranged to cooperate with said female die, a bifurcated lever with the legs of its bifurcated portion pivoted to the upper end of said guide post and with the upper end of the rod freely extending between said legs, said guide post being provided with vertically elongated slots, a pair of links arranged at opposite sides of said guide post and having their upper ends pivoted to the legs of the lever and their lower ends pivoted to said rod, the pivotal connections between the links and the rod, and between the post and the lever permitting removal of these parts for renewal purposes, and the pivotal connection of the links with the rod permitting adjustment of the links relative to said rod whereby the throw of the lever is made variable.

In testimony whereof I affix my signature.

MIKE BINDAS.
